Primary Examiner — Susan Bennett Hattan*Assistant Examiner* — Leanne Was(74) *Attorney, Agent, or Firm* — Ryan N. Carter(57) **CLAIM**

The ornamental design for a tile alignment and leveling device, as shown and described.

DESCRIPTION

FIG. 1 is a front perspective view of the tile alignment and leveling device with its locking members in the unlocked position;

FIG. 2 is a front perspective view of the tile alignment and leveling device with its locking members in the locked position;

FIG. 3 is a front view;

FIG. 4 is a rear view;

FIG. 5 is a first side view;

FIG. 6 is a second side;

FIG. 7 is a top view; and,

FIG. 8 is a bottom view.

The broken lines in the drawing depict portions of the tile alignment and leveling device that form no part of the claimed design.
